MISSILE INSTRUMENTATION PROTECTION MEANS

Robert S. Chamberlin, Las Cruces, N. Mex., assignor to
the United States of America as represented by the Sec-
retary of the Army

Filed Oct. 16, 1963, Ser. No. 316,781

2 Claims. (Cl. 102—92.5)

(Granted under Title 35, U.S. Code (1952), sec. 266)

The invention described herein may be manufactured and used by or for the Government for governmental purposes without the payment of any royalty thereon.

This invention relates to the protection of instrumentation and more particularly to instrumentation protection in missiles during flight and impact.

In order to retain the instrumentations intact during missile flight and impact, such instrumentation and its supports must be designed to withstand enormous acceleration and deceleration forces. The size, weight and shape of the instrumentation housing and the method by which the housing is held within the missile must be efficiently designed.

It is known that elements of equal weight are decelerated in a similar manner upon impact with the earth and that heavier elements decelerate over a longer period of time (greater distance) hence the rate of deceleration of heavier elements upon impact with the earth is less than the deceleration of lighter elements.

Also, under rapid acceleration during missile take-off and flight, great forces are exerted upon the relatively heavy instrumentation housing within the missile. It is extremely important therefore that the instrumentation housing be securely mounted to the missile wall. This is especially critical when large, heavy housings are utilized, since the force of acceleration on such housings is proportional to their weight.

It is therefore an object of the present invention to provide a heavy instrumentation housing designed to minimize deceleration forces on the instruments therein upon impact with the earth.

Another object of the present invention is to provide a mounting for heavy instrumentation housings which applies a pull rather than a push to the housing during acceleration of the missile.

A further object of the present invention is to provide a device for instrumentation protection that is simple and economical in construction.

Other objects and advantages of this invention will be readily understood by reference to the accompanying drawings wherein:

FIGURE 1 shows a partly cut-away view of the instrumentation housing of the present invention mounted in the forward portion of a missile; and

FIGURE 2 shows an enlarged perspective view of the instrumentation housing shown in FIGURE 1.

An instrumentation housing 10, shown in FIGURE 1, is mounted in the forward portion of a missile 12. The mounting of housing 10 is provided by two annular flanges

2

14 supporting housing 10 to missile 12. Additional support for housing 10 is provided by a rod 16 projecting forward from and attached to the forward end of housing 10. The distal end 18 of rod 16 is threadably secured to a truncated cone shaped element 20 by a nut 22. Element 20 is restrained by a third annular flange 24 disposed on the forward portion of the missile as shown in FIGURE 1.

Since housing 10 is considerably heavier than element 20 the inertial force during acceleration will be much greater on the heavier housing 10. This force will be transmitted through rod 16 and housing 10 will be primarily supported by element 20 and flange 24 by a pull on housing 10 during acceleration of missile 12.

An enlarged view of housing 10 is shown in FIGURE 2. Housing 10 comprises a rectangular center section 30 having an aperture 32 therein for containing the instruments 34. A pair of U-shaped portions 36 and 38 are rigidly affixed to the opposing sides 40 and 42 respectively of section 30 to provide additional protection for instruments 34.

Obviously many modifications and variations of the present invention are possible in light of the above teachings. While the foregoing is a description of the preferred embodiment of the invention, it is to be understood that various modifications and uses thereof may be resorted to that are within the spirit and scope of the appended claims.

I claim:

1. In a missile disposed for high accelerations and provided with instruments for recovery after impact, an impact protection device comprising: a heavy housing secured to said missile and disposed for support therein of said instruments; mounting means disposed for securing said housing in biased relation with said missile including a pair of annular flanges supporting said housing to the missile wall, a rod projecting forward from said housing, a truncated cone section secured to the forward portion of said missile and provided with an aperture therethrough disposed for receiving the distal end of said rod, a third annular flange carried in the forward portion of said missile and disposed for support of said cone section, and a nut threadably engaging said distal end of said rod for securing said rod and said cone section in tensile relation against said third flange.

2. An apparatus as set forth in claim 1 wherein said housing comprises: a heavy generally rectangular center section, said center section including an aperture therethrough disposed for mounting said instruments therein; a pair of U-shaped flanges secured to opposing sides of said rectangular center section for retention of said instruments in said aperture and for further instrument protection.
